(Cl. D90—20)

Fig. 1

*Fig. 3**Fig. 5**Fig. 4**Fig. 2*FIG. 1 is a perspective view of a tire embodying our new design, it being understood that the full line portion is repeated throughout the circumference of the tire, shown by means of broken lines;

FIG. 2 is an enlarged fragmentary side elevational view of the full line portion shown in FIG. 1;

FIG. 3 is an enlarged fragmentary plan of the full line portion shown in FIG. 1;

FIG. 4 is a sectional view taken substantially on the plane indicated by line IV—IV of FIG. 3, but also on the same scale as FIG. 2; and

FIG. 5 is a detailed sectional view taken substantially on the plane indicated by line V—V of FIG. 2, but on the same scale as FIG. 3.

The dominant features of our design reside in those portions shown in full lines in the drawings.

We claim:

The ornamental design for a tire, substantially as shown and described.
